United States Patent Office.

ALBERT J. GOODRICH, OF WOLCOTTVILLE, CONNECTICUT, ASSIGNOR TO TURNER, SEYMOUR, AND JUDDS, OF SAME PLACE.

Letters Patent No. 92,819, dated July 20, 1869.

IMPROVED TWINE-HOLDER.

The Schedule referred to in these Letters Patent and making part of the same.

To all whom it may concern:

Be it known that I, ALBERT J. GOODRICH, of Wolcottville, in the county of Litchfield, and State of Connecticut, have invented and made a new and useful Improvement in Twine-Holders; and I do hereby declare the following to be a full, clear, and exact description of the said invention, reference being had to the annexed drawing, making part of this specification, wherein—

Figure 1 is a vertical section of the said twine-holder and the friction-weight, and

Figure 2 is a plan of the lower part of the twine-holder.

Figure 3 is a detached elevation of the weight.

Similar letters denote the same parts.

A twine-holder has before been made in which two open-work shells are provided for holding the ball, and said shells have either been suspended by a ring or hook, or set upon a bracket, and a friction-brake has been applied, as in Letters Patent granted April 16, 1867, No. 63,950.

My present invention is an improvement upon the aforesaid Letters Patent, and consists in a globular or rounding weight in a socket at the lower side of the shell, to rest upon the twine, that is to be passed beneath the said weight and led out of an opening through said socket, so that said weight becomes a brake, to prevent the twine unwinding by the weight of the hanging cord.

In the drawing, *a* and *b* are the hemispherical shells, hinged together at *c*, and either suspended by a hook or ring, or supported by the stud *d*. Neither of these parts, however, is my invention.

The lower part of the shell *a* is made with a socket, *e*, in which is placed the globular or rounding weight *f*, that gives the necessary friction upon the cord passing below it, and out at the hole *i*.

This weight cannot become entangled in the cord, and, if desired, a lever-arm, *g*, may extend from the ball out through the shell and terminate as an eye, for the cord to pass through, in order that the ball may be lifted from the twine when said twine is pulled down.

What I claim, and desire to secure by Letters Patent, is—

1. The weight *f* and socket *e*, in combination with the shell of the twine-holder, as and for the purposes set forth.

2. The lever-arm *g*, with an eye at the end, in combination with the weight *f*, socket *e*, and twine-holder, as and for the purposes set forth.

In witness whereof, I have hereunto set my signature, this 21st day of May, A. D. 1869.

ALBERT J. GOODRICH.
